UNITED STATES PATENT OFFICE.

WILLIAM SHAPIRO, OF YARMOUTH, NOVA SCOTIA, CANADA

WASHING APPARATUS.

1,197,770.

Specification of Letters Patent. Patented Sept. 12, 1916.

Application filed May 10, 1916. Serial No. 96,618.

To all whom it may concern:

Be it known that I, WILLIAM SHAPIRO, a subject of the King of England, residing at Yarmouth, in the Province of Nova Scotia and Dominion of Canada, have invented certain new and useful Improvements in Washing Apparatus, of which the following is a specification, reference being had to the accompanying drawings.

10 This invention relates to certain improvements in washing apparatus and has relation more particularly to a device of this general character especially adapted for use in connection with household articles such as dishes, tableware, and the like; and it is an object of the invention to provide a device of this general character of novel and improved means whereby the same may be readily assembled when required or disassembled when not in use in order to occupy a minimum of space.

Furthermore it is an object of the invention to provide a novel and improved device of this general character including a removable article holder and a cleaning element together with means whereby the article holder may be adjusted relative to the cleaning element.

A still further object of the invention is to provide a novel and improved device of this type including a container supported independently of the article holder and which may be readily applied or removed as required.

35 The invention consists in the details of construction and in the combination and arrangement of the several parts of my improved apparatus whereby certain important advantages are attained and the device is rendered simpler, less expensive and otherwise more convenient and advantageous for use, all as will be hereinafter more fully set forth.

The novel features of the invention will 40 hereinafter be definitely claimed.

In order that my invention may be the better understood, I will now proceed to describe the same with reference to the accompanying drawings, wherein—

50 Figure 1 is a view partly in elevation and partly in vertical section of a washing apparatus constructed in accordance with an embodiment of my invention; Fig. 2 is a fragmentary view partly in section and partly in top plan illustrating certain details of my invention as herein set forth;

and Fig. 3 is a fragmentary view partly in plan and partly in section of the article holder as herein disclosed.

As disclosed in the accompanying drawings, F denotes the frame of my improved apparatus substantially in the form of an inverted U and having its vertical side members 1 provided adjacent their lower extremities with the openings 2 through which are adapted to be directed the opposed and reversely directed arms 3 of the base plate 4, said base plate 4 when in applied position being substantially flush with the lower or free ends of the vertical members 1 of the frame F. It is to be noted that the arms 3 afford a means whereby the plate 4 may be readily removed when the necessities of practice may require, and especially when the device is not in use and is to be stored away.

The upper or horizontal member 5 of the frame F is provided at substantially its center with an opening 6 through which is loosely directed the shank 7 of the brush B, the upper or free portion of the shank 7 having its periphery threaded and with which is engaged the head 8 of a diameter in excess of the diameter of the opening 6 and whereby the downward movement of the shank 7 is limited. Also detachably engaged with the upper or free end portion of the shank 7 is the operating member or handle 9 whereby the requisite axial rotation may be imparted to the brush B.

The brush B may be of any desired type, although it is preferred that the shank 7 be positioned adjacent an end thereof and that the brush be of a length less than one-half the length of the horizontal or upper member 5 of the frame F. It will be perceived that by having the shank 7 loosely disposed through the opening 6, said shank may be readily elevated when the requirements of practice may so necessitate. The plate 4 is of predetermined configuration and is adapted to have rested thereon the container 10 of desired capacity, said container 10 being provided with the diametrically opposed loops or eyes 11 adapted to be detachably engaged with the inwardly directed hook members 12 carried by the vertical members 1 of the frame F at a predetermined point intermediate the length thereof.

A denotes an article holder preferably of dish-like configuration and which is adapted to be arranged within the upper portion of

the container 10 when said container is employed and which is adapted to receive the articles to be cleansed. It is to be noted that the marginal portions of the holder A are provided with the slots 14 into which are adapted to be extended articles of tableware such as forks, spoons, or the like, and whereby said articles may be maintained in an effective position for cleansing purposes, and the intermediate portion of said holder A is provided with the openings 15 substantially semi-circular in form and into which cups or the like, to be cleansed, are to be seated.

Secured to the marginal portions of the holder A are the diametrically opposed up-standing rods 16 loosely directed through the openings 17 arranged adjacent the opposite ends of the horizontal member 5. The upper portions of said rods 16 have in threaded engagement therewith the nuts 18 or the like whereby it will be perceived that the holder A is supported by the horizontal member 5 and is capable of adjustment relatively thereto and independently of the container 10 and as the necessities of practice may require. It will also be perceived that after the plate 4 and the container 10 have been removed, the article holder A may also be readily removed by freeing the nuts 18 from the rods 16.

While under ordinary conditions it is preferred to employ the container 10 in which a supply of liquid is arranged, it will also be perceived that under certain conditions as in a sink or other receptacle, the container 10 may be omitted although this is not imperative.

It will also be self-evident that my improved washing apparatus may be employed with convenience and facility for the cleans-

ing of pots. When employed for this purpose the article holder A is removed and the pot to be cleaned inserted within the container 10. It will be understood that when employed for the purpose of cleansing pots, 45 the brush B will be longer than is disclosed in the accompanying drawings.

From the foregoing description, it is thought to be obvious that an apparatus constructed in accordance with my invention is 50 of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as 55 limiting myself to the precise arrangement 60 and formation of the several parts herein shown in carrying out my invention in practice.

I claim:

A washing apparatus comprising a frame 65 substantially in the form of an inverted U, an article holder, vertical rods carried by the article holder and loosely directed through the horizontal member of the frame, means 70 carried by the rods and coacting with said horizontal member for limiting downward movement of the rods, and a horizontally movable brush carried by the frame and positioned above the article holder.

In testimony whereof I hereunto affix my signature in the presence of two witnesses.

WILLIAM SHAPIRO.

Witnesses:

ANDREW C. PATTERSON,
CLAUDE L. SANDERSON.
